[57] CLAIM

The ornamental design of a video controller, as shown and described.

DESCRIPTION

FIG. 1 is a top, front and left side perspective view of a video controller showing our new design;
FIG. 2 is a top plan view thereof;
FIG. 3 is a bottom perspective view thereof;
FIG. 4 is a front perspective view thereof;
FIG. 5 is a rear perspective view thereof;
FIG. 6 is a right side perspective view thereof; and,
FIG. 7 is a left side perspective view thereof.

The broken lines in FIGS. 1, 2, 4, 6, and 7 represent environment only and form no part of the claimed design.
